UNITED STATES PATENT OFFICE.

GRACE MAE STEVENS, OF MIDDLETON SPRINGS, VERMONT.

DOUBLE ENVELOP.

1,347,797.

Specification of Letters Patent.

Patented July 27, 1920.

Application filed August 1, 1917. Serial No. 183,882.

To all whom it may concern:

Be it known that I, GRACE MAE STEVENS, a citizen of the United States, residing at Middletown Springs, in the county of Rutland and State of Vermont, have invented certain new and useful Improvements in Double Envelops; and I do hereby declare the following to be a full, clear, and exact description of the invention, such as will 10 enable others skilled in the art to which it appertains to make and use the same.

This invention relates to improvements in a double envelop.

The object of this invention is to provide 15 an envelop, which is so constructed as to provide two separate pockets or receptacles in the holder or envelop.

A further object of this invention is to provide an envelop especially adapted for 20 collections whereby separate matters may be held within the envelop and independently sealed.

A still further object of this invention is to provide an envelop with a pair of independent 25 pockets or compartments and a sealing flap adapted to be inserted into the upper open end of one compartment and sealed therein, this flap closing the openings of both compartments.

30 A still further object of this invention is to provide an envelop of this character, which will be simple, durable and comparatively inexpensive in construction, and one that can be manufactured and sold at a low 35 cost.

With these and other objects in view, the invention consists in the novel combination and arrangement of parts hereinafter more fully described and set forth in the claim 40 hereto appended.

In the drawings:—

Figure 1 is a top plan view of a blank embodying the construction of this invention,

45 Fig. 2 is a fragmentary top plan view of the blank illustrating the manner in which the lower edges of the body are folded back upon themselves,

50 Fig. 3 is a plan view illustrating the initial folding of the sides of the envelop upon the body,

Fig. 4 is a plan view illustrating the second folding movement of the envelop to provide the double compartments and with 55 the sealing tongue extended,

Fig. 5 is a plan view of the complete en-

velop partly broken away illustrating the manner in which the compartments are sealed,

Fig. 6 is a sectional view showing the open 60 or extended position to illustrate the double compartments or receptacles,

Fig. 7 is a sectional view taken on the line 7—7 of Fig. 5.

Like numerals of reference designate cor- 65 responding parts in all the figures of the drawings.

Referring to the drawings, the numeral 5 designates the envelop in its entirety or the blank from which the envelop is formed, 70 and it comprises a main rectangular body 6, on the lower longitudinal edge of which is formed the bottom flap 7, which is defined from the main body 6 by the dotted line 8. A sealing tongue 9 is formed at the upper 75 edge or end of the body 6 and has applied to its upper side transversely thereacross, a suitable adhesive material 10, the purpose of which will be hereinafter more fully de- 80 scribed.

A pair of side flaps 11 and 11' respectively are formed integrally with the opposite side edges of the main body 6 and the bottom flap 7 and are divided by the dotted lines 8', which facilitates the creasing of the blank 85 thereon, completing the envelop body.

The side flap 11 has a larger area than the flap 11' and the flap 11' has arranged on its upper side adjacent its vertical edge a suitable adhesive 12. Each of the side flaps 11 90 and 11' respectively are provided on their upper sides adjacent their lower edges with suitable adhesive 13. The side flaps 11 and 11' are divided from the lower portion of bottom flap 7 by vertical slit 14, thus defin- 95 ing the sealing members 16 on the side flaps 11 and 11' and bottom flap 7 as shown in Figs. 1 and 2 of the drawings.

The sealing members 16 are defined by the line 17, which extends thereacross and facilitates folding of the sealing tongues or flaps into the position shown in Fig. 2.

The side flaps are creased on the lines 18 and are adapted to have overlapping engagement with one another, flap 11' being 105 positioned beneath flap 11, and the adhesive 12 is sealed to the inner face of the side flap 11, thus providing a single compartment. When the side flaps 11 and 11' are folded on the line 8 and 8', this single compartment 110 is divided into two compartments, designated A and B in Fig. 6 of the drawings.

The sealing tongue 9 is bent on the line 19 and is adapted to be inserted into the upper open end of the compartment A and sealed to the sealing tongues 16 and the adhesive 10 of the sealing tongue 9 is sealed to the inner face of element 7 of compartment A to effectively and permanently close the compartments A and B respectively.

In use, the envelop blank is cut in the manner described. The sealing tongues 16 are bent in the manner illustrated in Fig. 2 by creasing the same on the lines 17, the side flaps 11 and 11' are then bent on the dotted lines 18 in overlapping engagement and the side flap 11 is sealed to the upper side of the side flap 11' as shown in Fig. 3 by moistening the adhesive 12. The sealing of the side flap 11 to the side flap 11' forms the compartment as shown. The blank is then bent on the dotted line 8 and 8' forming the compartments A and B respectively. The sealing tongue is then inserted into the upper open end of the compartment A as shown in Fig. 7, the adhesive 10 and 13 is then moistened and pressure is applied, thus effectively closing both of the compartments and the envelop is assembled and ready to be transmitted through mails or otherwise.

30 What is claimed is:

A double compartment envelop formed from a blank having a rectangular body

portion, a tongue extending from one side edge of the body intermediate its length to provide a closure flap, the body portion being provided with slits extending transversely thereof from the opposite edge and in alinement with the ends of the closure flap to provide intermediate and end tongues, the intermediate and end tongues being bent back upon themselves and the end tongues being gummed, said body being folded at the slits with the end portions extending in overlapping relation and one of the end portions having its end edge portion gummed and adhering to the edge portion of the second end portion, said blank when folded forming a receptacle having open ends and said receptacle being folded transversely intermediate its length and the closure flap extending from one of the open ends of the receptacle being tucked into the second open end to close the open end and adhering to the gummed end tongues and having its opposite face gummed for adhering to the intermediate tongues to hold the receptacle in a folded position.

In testimony whereof I affix my signature in presence of two witnesses.

MRS. GRACE MAE STEVENS.
